UNITED STATES PATENT OFFICE.

ERNEST E. CULLEN, OF NEW BALTIMORE, MICHIGAN, ASSIGNOR OF ONE-HALF TO
GEORGE E. VERNIER, OF FAIR HAVEN, MICHIGAN.

TRIPLE-JAWED WRENCH ATTACHMENT FOR HAMMERS.

Application filed May 29, 1922. Serial No. 564,552.

To all whom it may concern:

Be it known that I, ERNEST E. CULLEN, a citizen of the United States, and residing at New Baltimore, county of Macomb, and 5 State of Michigan, have invented a new and Improved Triple-Jawed Wrench Attachment for Hammers, of which the following is a specification.

This invention relates to wrench attachments for hammers and other tools, and has 10 for its principal object the provision of a pipe-gripping wrench of convenient size and compact construction that can be readily kept in a small drawer, tool kit, etc., and 15 which is arranged to be quickly mounted on to the head or claw of an ordinary hammer or like tool when desired for use.

Another object of my invention is the provision of a wrench attachment having three 20 jaws arranged with teeth inclined to bite into the periphery of a pipe when pressure is applied to the handle of the hammer to which the jaw member is attached.

The above and other objects of my invention will be apparent from the following description wherein reference is made to the accompanying drawing illustrating a preferred embodiment of my invention, and 25 wherein similar reference numerals designate similar parts throughout the several views.

In the drawings:—

Fig. 1 is a side elevation of my triple-jawed wrench attachment mounted over the 30 claw portion of an ordinary hammer in position for use in turning pipes or the like; and

Fig. 2 is a perspective view of the wrench attachment.

Referring now to the drawings my improved wrench attachment is shown as formed with a V-shaped body portion 5 having teeth 6 on its opposite jaws to grip the rounded surface of a pipe or coupling which 40 it is desired to turn. The teeth 6 are preferably so inclined that the dentations will bite into the opposite sides of the pipe surface when the body portion 5 is rotated in the direction of the arrow in Fig. 1, which 45 is the natural direction of rotation for the majority of persons who are "right-handed" in their actions. It will be understood, however, that the teeth 6 on the jaws of the body member 5 may be inclined in the opposite direction if desired. A third jaw 7 having 50

teeth 8 inclined so as to bite into the rounded surface of the pipe or the like, is connected with one extremity of the V-shaped body member 5. As herein shown the jaw member 7 is formed as a U-shaped yoke apertured at its free ends and of sufficient width to pass over the edges of the body member 5 so that the apertures therein will align with an aperture in one extremity of the V-shaped member 5. The aligned apertures in the members 5 and 7 receive the ends of a link 9, which secures the jaw members in position and also forms the means whereby my wrench attachment may be quickly mounted upon the head or claw of an ordinary hammer or like tool. Thus in Fig. 1 the link 9 is shown in position over the claw of a hammer 10, the bight portion of the link seating in the crotch between the claw portion and the handle-receiving portion of the hammer 10. When mounted on the hammer in this position the jaw member 7 is adapted to lie flat against the forward extremity of the hammer head, and the V-shaped body member 5 may be swung on the pivot portion of 60 the link 9 so as to encircle pipes or couplings of different diameters. Thus a large pipe would be encircled by moving the free end of the body portion 5 away from the jaw member 7 to enlarge the space between the 65 teeth 6 and 8 on the respective jaws. A smaller pipe would be gripped by reducing the space between the teeth on the several jaws by swinging the free end of the body portion 5 toward the member 7 until the 70 teeth on all three jaws are in engagement with the surface of the pipe. To permit gripping relatively small pipes the opening in the U-shaped jaw member 7 is of sufficient width to permit the free end of the body 75 member 5 to pass therethrough.

In operation my improved wrench attachment is secured upon the head or claw portion of a hammer by passing the link 9 thereover, substantially as shown in Fig. 1, 80 whereupon the V-shaped body member is swung into open position and passed around a pipe, coupling, nut, or the like, and then 85 swung toward the jaw member 7 until the teeth 6 and 8 on the several jaw members 90 engage the pipe surface. By then rotating the hammer head in the desired direction the pipe or nut may be unscrewed or turned 95 into position. The leverage given by the length of the hammer handle is ordinarily 100 105 110

sufficient to tighten or release all the usual sizes of pipes or nuts in common use. It will be understood that if the pipe or nut is to be rotated in one direction the claw portion of the hammer is arranged at the right-hand side of the pipe or nut, and if the pipe or nut is to be rotated in the opposite direction, the claw portion of the hammer is arranged at the left-hand side thereof. With this reverse arrangement of the wrench attachment the teeth on the several jaws will all engage the surface of the pipe or nut and give a powerful gripping surface.

15 While it will be apparent that the illustrated embodiment of my invention herein disclosed is well calculated to adequately fulfill the objects and advantages primarily stated, it is to be understood that the invention is susceptible to variation, modification, and change within the spirit and scope of the subjoined claims.

20 Having described my invention, I claim:

25 1. A wrench attachment for hammers and the like, having a link adapted to be removably secured upon a hammer head, a jaw portion pivotally mounted upon the link and adapted to rest against the forward extremity of the hammer head, and a V-shaped body portion pivoted upon the

link and movable relatively to said jaw portion.

2. A wrench attachment for hammers and the like, having a link adapted to be 35 removably secured upon a hammer head, a jaw portion pivotally mounted upon the link and adapted to rest against the forward extremity of the hammer head, and a V-shaped body portion pivoted upon the 40 link and movable relatively to said jaw portion, said jaw portion and body portion being provided with teeth inclined to bite into the surface of a pipe when the hammer head is rotated.

3. A wrench attachment for hammers and the like, having a link adapted to be removably secured upon a hammer head, a U-shaped jaw portion pivoted upon the link, and a V-shaped body member pivoted 50 at one extremity upon the link between the legs of the U-shaped member, the other extremity of said V-shaped member being adapted to pass between the legs of the U-shaped member.

45 In witness whereof I hereunto set my hand.

ERNEST E. CULLEN.
